[57] CLAIM

The ornamental design for a combined portable internal combustion engine and tool, as shown and described.

DESCRIPTION

FIG. 1 is a left side elevational view of a combined portable internal combustion engine and tool showing our new design;

FIG. 2 is a right side elevational view thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is an enlarged left side elevational view of the engine;

FIG. 8 is an enlarged right side elevational view thereof;

FIG. 9 is an enlarged top plan view thereof;

FIG. 10 is an enlarged bottom plan view thereof;

FIG. 11 is an enlarged front elevational view thereof; and

FIG. 12 is an enlarged rear elevational view thereof.

FIGS. 7-12 are shown separate for clarity of illustration only.
